CLAIM

The ornamental design for a coil component, as shown and described.

DESCRIPTION

FIG. 1 is a front elevational view of a coil component showing our new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a perspective view thereof; and,

FIG. 8 is a perspective view thereof, shown in a used condition.

The evenly spaced broken lines depict unclaimed parts of the coil component and form no part of the claimed design.
